CLAIM

The ornamental design for an adjustable risking desk, as shown and described.

DESCRIPTION

FIG. 1 is a perspective view showing an alternative new design for an adjustable risking desk;

FIG. 2 is a front view of the adjustable risking desk of FIG. 1;

FIG. 3 is a rear view of the adjustable risking desk of FIG. 1;

FIG. 4 is a left-side view of the adjustable risking desk of FIG. 1;

FIG. 5 is a right-side view of the adjustable risking desk of FIG. 1;

FIG. 6 is a top view of the adjustable risking desk of FIG. 1; and,

FIG. 7 is a bottom view of the adjustable risking desk of FIG. 1.

The dashed lines showing portions of the adjustable risking desk are included for the purpose of illustrating environment and form no part of the claimed design.

Where the figures show the article broken away, they are understood to indicate unclaimed length or width.
